COMBINATION CIGARETTE HOLDER AND
ASH TRAY

Gretyl Howard, Sioux City, Iowa

Application June 22, 1950, Serial No. 10,695

Term of patent 14 years

(Cl. D85—8)

To all whom it may concern:

Be it known that I, Gretyl Howard, a citizen of the United States of America, residing at Sioux City, in the county of Woodbury and State of Iowa, have invented a new, original, and ornamental Design for a Combination Cigarette Holder and Ash Tray, of which the following is a specification, reference being had to the accompanying drawing, forming part thereof.

In the drawing

Fig. 1 is a side elevational view of a combination cigarette holder and ash tray, showing my new design;

Fig. 2 is an end elevational view taken from the left end of Fig. 1.

Fig. 3 is an end elevational view taken from the right end of Fig. 1.

Fig. 4 is a perspective view of the interiorly threaded cap of the combination cigarette holder and ash tray, looking inwardly thereinto as same is removed from the body of the device.

Fig. 5 is an end elevational view of the body of the device, taken from the right end of Figure 1, with the threaded cap of Fig. 4 removed from the body of the device.

I claim:

The ornamental design for a combination cigarette holder and ash tray, as shown.

GRETYL HOWARD.
